UNITED STATES PATENT OFFICE.

OTTO ZIMMERMAN, OF NEW YORK, N. Y.

TERMINAL CONNECTER FOR ELECTRICAL CONDUCTORS.

Application filed December 1, 1919. Serial No. 341,806.

To all whom it may concern:

Be it known that I, OTTO ZIMMERMAN, a citizen of the United States, and a resident of the city of New York, borough of the Bronx, in the county of Bronx and State of New York, have invented a new and Improved Terminal Connecter for Electrical Conductors, of which the following is a description.

10 This invention relates to terminal connectors for electric conductors, especially to terminals for stranded conductors, which can be permanently and quickly attached without soldering to the end of a conductor 15 by mechanical means to entirely inclose the conductor end in a metallic casing.

The invention has for its general objects to provide a terminal for flexible and other electric conductors, which can be made of 20 sheet metal easily cut and formed under a punch press and firmly attached to a conductor with specially formed pliers or hand clamps to firmly bind both the naked and insulated ends of a flexible electrical conductor 25 to prevent stripping or unraveling the insulation and holding the stranded wires and the insulation in an entirely inclosed metallic casing allowing a large area of electrical contact and bringing the strain 30 of the clamping screw on the casing containing the naked conducting wires.

A more specific object of the invention is to produce a terminal which can be attached to electric conductors by mechanical 3 means and not be affected by heat, to surround and entirely inclose the naked and insulated ends of a conductor wire in a rigid metal casing in such a manner that the clamping screw brings the strain directly 40 upon the naked end of the conducting wire held within the terminal casing. One of the principal uses for this terminal is on rheostats, heating apparatus, arc lamps and all electrical devices generating heat where 45 a soldered terminal could not be used to advantage, although not necessarily limited to this use, but available for use in all cases where a terminal can be applied to conduct electric current.

50 With such objects in view, and others which will appear as the description proceeds, the invention comprises various novel features of construction and arrangement of parts which will be set forth with particularity in the following description and claims appended hereto.

Reference is to be had to the accompanying drawings forming a part of this specification, it being understood that the drawings are merely illustrative of practical examples 60 of the invention.

Figure 1 is a perspective view of a terminal connecter embodying my invention, showing the same attached to a flexible electrical conductor;

65 Figure 2 is a longitudinal vertical section through the connecter of the form shown in Figure 1 and the conductor;

Figure 3 is a plan view of the parts shown in Figures 1 and 2 but showing the connecter before being flanged over in the final step of affixing the same to the conductor;

70 Figure 4 is a transverse vertical section on the line 4—4, Figure 2;

Figure 5 is a perspective view of the connecter before being applied to the conductor;

75 Figure 6 is a transverse vertical section of another form of my improved connecter;

Figure 7 is a plan view of a connecter 80 presenting end clips for use in tapping off a branch from a main feed wire without cutting the latter;

Figure 8 is a side elevation of the device 85 shown in Figure 7;

Figure 9 is a plan view of the device shown in Figures 7 and 8 before being flanged over onto the conductor;

Figure 10 is a plan view of my improved connecter of a form permitting of its being 90 applied to the conductor by a movement lengthwise thereof instead of laterally.

Figure 11 is a longitudinal vertical section similar to Figure 2 but showing a further modification;

95 Figure 12 is a perspective view of an element employed in the construction shown in Figure 11.

Referring at first particularly to Figures 1 to 5 of the drawing, A designates a conductor, and B my solderless terminal connecter applied thereto. The connecter is formed with an eyelet portion 15 and also preferably and advantageously with a clip portion 16. The eyelet portion 15 is formed with an interior tubular stud 17 and with an outer peripheral rim 18, said stud and rim being upstanding and substantially parallel and also concentric in the original form of the connecter, as shown in Figures 110 3 and 5. If the conductor A has insulation a, the insulation is removed from the strands

where they engage the connector B so that when the connector is applied it will have a good electrical connection with the conductor.

5 The connector in the form referred to and also in the other forms hereinafter referred to, is so arranged that the eyelet portion presents at the tubular stud or at the peripheral flange, or both, a member or 10 members of a character to be bent or flanged down onto the conductor to have clamping engagement therewith. In the form shown in Figures 1 to 5 and which is preferred, both the inner stud 17 and the rim 18 have a 15 height to both be flanged down as in Figures 1, 2 and 4, said flanges, designated 19 and 20, abutting at the annular medial line of the conductor, the exposed portion a^2 of which is bent about the stud 17 in the annular 20 channel or pocket 21 formed by said stud and rim so that the clamping down of the flanges 19, 20 onto the conductor will give the same a more or less flattened form as shown in Figures 2 and 4.

25 The clip portion 16 is curved transversely and made approximately U-shaped to receive the adjacent insulated conductor portion and the sides of the clip when the connector is applied to the conductor are bent down- 30 wardly toward each other into close relation to form about the conductor a casing of substantial unbroken continuity. It is to be understood that the bending down of the flanges 18 and 19 and the sides of the clip 35 16 is in practice done in a machine under pressure so that when the connector is once applied it is impossible to pull the connector out as the strands of the conductor are tightly clamped by the eyelet portion of the 40 connector and the adjacent insulation and strands are firmly clamped by the clip portion.

In the form shown in Figure 6 the eyelet portion 15^a and clip portion 16^a of the 45 connector, B', are in the main similar in form to the same parts shown in Figures 1 to 5, the difference being that the tubular stud 17^a and peripheral rim 18^a forming the channel 21^a are given a height so that 50 both may be flanged over onto the clamped part a^2 of conductor A' and overlap each other as at 19^a, 20^a, each of said flanges being of a width to completely bridge the channel 21^a or substantially so. The form of my in- 55 vention shown in Figures 7 to 9 constitutes a double-ended connector, B^a, for use in tapping off a branch from a main feed wire A^a without cutting the strands for which purpose said connector presents diametri- 60 cally opposite clip portions 16^a. The eyelet portion 15^a of the connector presents a central tubular stud 17^a and curved rim members 18^a at opposite sides of the stud. I have shown the connector 15^a in this form 65 of my invention with the rim members 18^a

and the stud 17^a both flanged over to form clamp flanges 19^a, 20^a meeting at the medial line after the manner of the first described construction but it will be understood that said flanges may be similar to the flanges 19^b, 20^b of Figure 6. The conductor or feed wire A^a at the exposed part a^2 is divided centrally and spread laterally in the arcuate channels 19^b formed between the tubular stud 17^b and the rim portions 18^b.

75 In the forms described, the connector is dropped onto the binding post (not shown), through the central opening presented by the tubular stud. In Figure 10 a side opening 22 extends through rim flange 18^c and tubular stud 17^c approximately radially to said stud. In this form I have illustrated the stud and rim portion as both turned over onto the conductor to present abutting flanges 19^c, 20^c. The clip portion 16^c is the same as in the other forms to be clamped onto the adjacent insulated conductor portion A^c.

80 In all forms of the invention the clip 16 preferably is indented as at 23 to depress the same and form an interlocked engagement with the insulation surrounding the conductor.

85 In Figure 11 the eyelet portion 15^d of the connector and the clip 16^d are employed in connection with a cover plate 24 of the form shown in Figure 12. Said plate is in ring form to be accommodated in the channel 21^d on top of the conductor and thereby lie beneath the overturned flanges 19^d, 20^d of the connector. A tang or arm 24^d at one side of 90 said plate extends into the clip 16^d to be clamped down by the same when flanged over onto the conductor.

95 I would state in conclusion that while the illustrated examples constitute practical embodiments of my invention, I do not limit myself strictly to the mechanical details herein illustrated, since manifestly the same can be considerably varied without departure from the spirit of the invention as defined in the appended claims. For example, either of the flanges 19^a, 20^a, Figure 6, may obviously be omitted and also the flanged-over portions may be of unbroken continuity 100 or split radially as will be obvious.

105 Having thus described my invention, I claim:

110 1. As a new article of manufacture, a unitary terminal connector for electrical conductors, including a tubular stud, and an outer rim spaced from the stud so that the two constitute inner and outer walls of a channel adapted to accommodate a conductor, both of said walls being of a height to 115 permit being bent over into flange form to overlie said channel for clamping the conductor therein.

120 2. A terminal connector for electrical conductors, including a tubular stud, and an 125

outer rim spaced from the stud so that the two constitute inner and outer walls of a channel adapted to accommodate a conductor, said walls being of a height to permit 5 of both being bent downwardly toward each other in approximately abutting relation in the same plane for clamping the conductor in said channel.

3. As a new article of manufacture, a connector for electrical conductors including a 10 tubular stud and a rim portion outside of the stud, said rim portion and stud forming walls of a channel therebetween; together with an element fitting the connector between 15 said stud and rim portion, both walls

of the channel being adapted to be flanged over onto said element.

4. A terminal connector for electric conductors consisting of a single member comprising a central hollow tubular stud and an outer peripheral flange joined thereto by an integral bottom member thereby forming 20 inner and outer walls of a channel to receive the conducting wires, said flanges and stud being of a height to permit both being closed down toward each other completely 25 enclosing the naked conducting wire and having an integral clip portion bendable about the insulated portion of conductor.

OTTO ZIMMERMAN.
